(57) **CLAIM**

The ornamental design for an ultrasonic transducer for a fish finder, as shown.

DESCRIPTION

FIG. 1 is a top side perspective view of the ultrasonic transducer for a fish finder showing my new design; FIG. 2 is a left side view, with right, front and back sides all the same due to the rotational symmetry of the ultrasonic transducer;

FIG. 3 is a top view thereof;

FIG. 4 is a bottom view thereof;

FIG. 5 is a bottom side perspective view thereof; and,

FIG. 6 is a cross-sectional view taking along the line 6-6 of FIG. 2.

1 Claim, 3 Drawing Sheets
